UNITED STATES PATENT OFFICE

145,812

DESIGN FOR A COOKIE CUTTER

Marcia M. Meyers, Poplar Grove, Ill.

Application December 6, 1945, Serial No. 124,406

Term of patent 14 years

(Cl. 44—29)

To all whom it may concern:

Be it known that I, Marcia M. Meyers, a citizen of the United States, residing at Poplar Grove, in the county of Boone and State of Illinois, have invented a new, original, and ornamental Design for Cookie Cutter, of which the following is a specification, reference being had to the accompanying drawing, forming part thereof.

In the drawing:

I claim.

The ornamental design for a cookie cutter, as shown.

MARCIA M. MEYERS.
